UNITED STATES PATENT OFFICE.

WILLIAM D. FORSYTH, OF YOUNGSTOWN, OHIO, ASSIGNEE TO RAILWAY PRODUCTS CORPORATION, OF BUFFALO, NEW YORK, A CORPORATION OF NEW YORK.

DRAFT-GEAR.

1,130,387.

Specification of Letters Patent.

Patented Mar. 2, 1915.

Application filed December 4, 1913. Serial No. 804,679.

To all whom it may concern:

Be it known that I, WILLIAM D. FORSYTH, a citizen of the United States, residing in the city of Youngstown, county of Mahoning, and State of Ohio, have invented a new and useful Improvement in Draft-Gears, of which the following is a specification.

My invention relates to improvements in draft gears.

10 One of the objects of my invention is to provide a construction in draft gears which will cause compressed air and springs to co-operate to take up some of the motions of cars when started and stopped.

15 My invention consists, among other things, of a draft gear, the construction of which provides for the use of compressed air and springs in co-operation with one another to absorb and regulate the motion of bodies 20 of cars when starting and stopping and in the devices and constructions hereinafter more specifically described and claimed.

In the accompanying drawing, which forms part of the specification, and in which 25 like reference characters refer to like parts throughout the several views, Figure 1 is a horizontal section through a draft gear embodying my invention; Fig. 2 is a side elevation of the draft gear shown in Fig. 1 30 with the springs removed; Fig. 3 is an end elevation of a plate and cylinder forming part of the draft gear; Fig. 4 is a side elevation of the part shown in Fig. 3; Fig. 5 is an end elevation of a follower plate and piston 35 forming part of the draft gear; Fig. 6 is a side elevation of the part shown in Fig. 5.

In the draft gear which I have shown as embodying my invention, a draw bar 1, the coupler end of which is not shown, is fastened by rivets 3 to a yoke 2. Mounted 40 within the yoke 2 are two follower plates 4, each having an integral piston 5 extending toward each other. Between the pistons 5 is a plate 7 having integral cylinders 6 extending 45 in opposite directions therefrom. The plate 7 is disposed so that when the end of one piston 5 is near the bottom of one of the cylinders 6, the end of the other piston 5 is near the open end of the other cylinder. 50 Mounted in the plate 7 are check valves 8, each communicating with the closed end of one of the cylinders 6. The check valves 8 may be of any suitable construction which 55 will prevent escape of air from the cylinders 6, but will allow air to enter said cylinders.

In the side wall of each cylinder 6 is constructed a groove, 9, the bottom of which is inclined, so that its greatest opening is at the edge of the bore at the open end of said cylinder 6, said groove gradually disappearing in the sides of said cylinder before it reaches the closed end of said cylinder. 60

Spiral springs 10, 10, are placed around the ends of cylinders 6, 6, and around the pistons 5 as shown in Fig. 1. The springs 65 10 press the follower-plates 4 against the yoke 2 and the rear end face of the draw-bar respectively, and thus cause the pistons 5 of said follower-plates to follow the movements of said yoke. The plate 7 is fixed with relation to draft sills 11, 11, by cleats 12, 12, 12, 70 12 affixed to said sills by rivets 13.

When a car to which said draft gear is attached is suddenly stopped, the piston 5, next to draw-bar 1, is driven into the bore 75 of the adjacent cylinder 6, and as it passes into said cylinder the air escapes through the inclined groove 9 until the piston completely fills the bore of said cylinder, when the air is compressed within the cylinder, 80 affording a cushion which opposes further motion of the car. While the compressed air is thus opposing the motion of the car, the movement of the follower-plate 7 is also compressing spiral spring 10, surrounding the 85 same, and the cylinder 6. Thus the compressed air in the cylinder and the spiral spring are co-operating to oppose the motion of the car involved in the stopping of the same. The reverse of these operations takes 90 place in the remaining cylinder 6 and in the spiral springs surrounding the same, the valve 8 permitting the ingress of air into said cylinder as the piston 5 is being withdrawn therefrom. 95

When the draft gear hereinbefore described is used upon a car and the car is stopped, about the first opposition that there is to the thrust caused by the stoppage of the car on the car itself is the resistance of the cushion 100 of air being compressed by the movement of the piston in the cylinder next the draw-head. At the same time the spring mounted on the last mentioned cylinder more slowly takes up the opposition to such thrust and 105 finally both are co-operating to oppose it. At the same time the cylinder next to the yoke end and away from the draw-head is having its piston withdrawn and is filling 110 with air and the spring upon that cylinder.

is extending, so that when the recoil which always takes place, happens, the recoil is cushioned first against the air in the cylinder last mentioned and upon the spring mounted 5 upon said cylinder, and they together then co-act to resist the recoil, until finally, by the repeated action of the draft gear, the effects of the thrusts and recoils are absorbed without undue shock. When the car is started, 10 the shocks of initial pull and the recoil connected therewith are absorbed in the same way.

The draft gear herein described is particularly effective in taking care of the recoils 15 occurring in the starting and stopping of cars.

What I claim as my invention is:

1. In a draft gear, a plate secured to the draft sills of a car and having cylinders 20 with open ends projecting therefrom in opposite directions, a draw-bar yoke, follower-plates mounted within said yoke and each having a piston adapted to enter one of said cylinders, a spiral spring mounted between 25 each follower-plate and said plate and surrounding the corresponding cylinder, said follower-plates following the movements of said yoke, the lengths of said cylinders and said pistons being such that when the end of 30 one piston is near the bottom of one cylinder the end of the other piston is near the open end of the other cylinder, said pistons operating to draw air into said cylinders and to

compress it therein as said pistons are respectively withdrawn from and pushed into 35 said cylinders, the inside wall of each of said cylinders having a groove therein decreasing in cross-section from the open end of said cylinder to a point spaced from the bottom thereof. 40

2. In a draft gear, cylinders each having one end open and fixed to the draft sills of a car, a draw-bar yoke, pistons supported by said yoke and following the movements thereof, said pistons being adapted to enter 45 said cylinders and being arranged so that when one piston is near the bottom of one cylinder, the other piston is partly out of the other cylinder, an opening communicating with each cylinder and restricting the 50 exhaust of air from the cylinder during part of the movement of said piston in entering said cylinder, said opening terminating at a distance from the bottom of said cylinder, and a check valve communicating with each cylinder near the bottom thereof and adapted to prevent the escape of air therefrom while permitting the entrance of air. 55

In testimony whereof I have hereunto subscribed my name in the presence of two 60 subscribing witnesses.

WILLIAM D. FORSYTH.
